UNITED STATES PATENT OFFICE.

THEODORE R. CHANDLER, OF DAVENPORT, IOWA.

CAR-DOOR HANGER.

Application filed December 1, 1922. Serial No. 604,134.

To all whom it may concern:

Be it known that I, THEODORE R. CHANDLER, a citizen of the United States, residing at Davenport, in the county of Scott and State of Iowa, have invented a new and useful Car-Door Hanger, of which the following is a specification.

This invention relates to improvements in sliding doors and more particularly to 10 hangers for mounting a door on one side of a car or the like which permit the door to be moved to open or closed position and prevent the door from being detached and lost while the car is in transit. 15 Hangers for car doors have been constructed to move laterally and longitudinally on a track but such devices are of complicated, expensive construction, easily liable to get out of order and dependent upon manual operation to force the door laterally out of its opening and one object of the invention is the provision of resilient means operating upon the unlocking of the door to force the door outwardly from its opening 20 to clear the wall of the car and permit longitudinal movement of the door.

Another object is the provision of a rigid hanger having its main members adapted for economical construction from standard 30 rolled sections.

Another object is to provide an improved supporting and locking device which operates to support the door and also permits the door to be moved separably toward or 35 away from the car wall and parallel thereto.

Another object is the provision of improved means for forcing the door into closed position and locking the same.

The objects of the invention thus generally stated, together with other and ancillary advantages, are attained by the construction and arrangement illustrated in the accompanying drawing forming part hereof, but it will be apparent that various 45 changes in the form, construction and arrangement of the parts may be made by those skilled in the art without departing from the spirit and scope of the invention as expressed in the appended claims.

50 In the drawings, Figure 1 is an elevation of a sliding door mounted on a car and equipped with the device of my invention. Fig. 2 is an enlarged scale sectional view on the line 2-2 of Fig. 1. Fig. 3 is a detail sectional view on the line 3-3 of Fig. 2. Fig. 4 is an enlarged scale detail sectional view on the

line 4-4 of Fig. 1. Figs. 5 and 6 are detail views.

The construction which I have selected for purposes of illustration is designed primarily for use with a freight car, although it is to be understood that the invention is not limited to use on a car or other vehicle, but may be used on buildings such as warehouses, icehouses and the like.

The construction comprises in general a two-ply sliding door 1 supported at its upper end by a track 10 and adapted to close an opening 21 in the side wall 22 of the car. The track 10 comprises a Z bar rigidly fastened to the side wall of the car with its outer leg projecting downwardly and its web extending horizontally.

The hanger comprises an angle 7 and a channel 8 fastened together as by rivets 23 and rigidly fastened to the door 1. The channel 8 substantially encloses the track 10 and provides a mounting for the rollers 19 which support the door and permit its easy movement longitudinally. Pins 20 provide journal bearings for rollers 19 and are fastened to the web of the channel 8 by nuts 11. A Z bar 14 and a plate 16 mounted on the wall 22 provides a guide for the lower end of the door.

A vertical rod 6 is rotatably fastened to the door 1 by a strap 5 and extends up through the angle 7 and the channel 8 terminating at its upper end with a cam 18 and extends down through the angle 13 terminating at its lower end with a cam 17. The rod 6 is pivotally supported on the angle 7 by the cam 18 and may be rotated by an arm 2 which is mounted on the rod toward its lower end so as to be accessible from the ground.

The cam 17, below the angle 13, acts as a stop against the upper flange of the Z bar 14, to limit the outward movement of the door.

The cams 17 and 18 are fastened on rod 6 at an angle of ninety degrees with each other (Fig. 5) and with the arm 2 positioned so as to make an angle of one hundred eighty degrees with the cam 17 (Figs. 1 and 2). A rod 4 fastened to the wall 22 and a pin 3 are provided to fasten and seal the door 1 in the well known manner.

In Figs. 1 and 2 the door is shown in closed position, with the cam 18 in contact with the Z bar 10 and the cam 17 turned parallel to the door.

To open the door the pin 3 is removed and the arm 2 is rotated through ninety degrees. This movement tends to disengage the cam 18 from the Z bar 10 and turns the cam 5 17 into engagement with the guide bar 16 thereby forcing the lower end of the door outwardly to clear the wall of the car. The upper end of the door is simultaneously forced outwardly by the action of a spring 9 10 (Figs. 2 and 6) which is mounted on the web of the channel 8 by means of bolts 12 so as to bear constantly against the downwardly projecting leg of the Z bar 10. The spring 9 acts to yieldingly hold the door outwardly away from the wall 22 and is made 15 sufficiently rigid to move the door and hanger outwardly and keep the cam 18 in contact with the Z bar 10 as the cam is rotated. The rollers 19 are slid longitudinally 20 on the track by the lateral movement of the door and are of sufficient length that when in their outermost position they have ample bearing on the Z bar 10. The door 1 can then be rolled along the track 10 until it 25 strikes the stop 15.

Thus it will be seen that I have provided an improved supporting and locking device of substantial construction for a car door or the like which is manually operable to force 30 the door laterally into closed position and which upon release of the locking device automatically moves the door and hanger outwardly from the car to permit of its longitudinal movement to open position.

35 I claim as my invention:

1. The combination with a wall of a door set into the side thereof, a Z bar track fastened to the wall, a hanger comprising a channel rigidly fastened to the door, and 40 having rollers mounted on the web of the channel adapted to roll longitudinally along the web of said Z bar and to be slid transversely on said Z bar web, a vertical rod rotatably mounted on the door, a Z bar guide 45 member on said wall, at the bottom of the door, a cam on the upper end of said rod adapted to force the door laterally toward said wall upon rotation of said rod and to limit the outward lateral movement of the 50 door and hanger, and a cam on the bottom end of said rod adapted to limit the lateral movement of the door in the bottom guide member.

2. The combination with a wall of a door set into the side thereof, a Z bar track fastened to the wall, a hanger comprising a channel rigidly fastened to the door, and having rollers mounted on the web of the channel adapted to roll longitudinally along 60 the web of said Z bar and to be slid transversely on said Z bar web, a vertical rod rotatably mounted on the door, a Z bar guide member on said wall, at the bottom of the door, a cam on the upper end of said 65 rod adapted to force the door laterally to-

ward said wall upon rotation of said rod and to limit the outward lateral movement of the door and hanger, and a resilient member mounted on the channel in contact with said first mentioned Z bar to yieldingly hold the 70 channel and door outwardly from the wall.

3. The combination with a wall of a door set into the side thereof, a Z bar track fastened to the wall, a hanger comprising a channel rigidly fastened to the door, and having rollers mounted on the web of the channel adapted to roll longitudinally along the web of said Z bar and to be slid transversely on said Z bar web, a vertical rod rotatably mounted on the door, a Z bar 75 guide member on said wall, at the bottom of the door, a cam on the upper end of said rod adapted to force the door laterally toward said wall upon rotation of said rod and to limit the outward lateral movement of the door and hanger, a cam on the bottom end of said rod adapted to limit the lateral movement of the door in the bottom 80 guide member and a resilient member mounted on the channel in contact with said first mentioned Z bar to yieldingly hold the 85 channel and door outwardly from the wall. 90

4. The combination with a car having a door opening and sliding door, of hanging mechanism at the top of the door comprising a track and a hanger engaging said track, a device operable to force said door laterally into the door opening, said device comprising a vertical rod rotatably mounted on the door and having a cam projecting from its 100 upper end to engage said track as the rod is rotated to force the door inwardly, a guide at the bottom of the door, a cam on the bottom of the rod adapted to engage the guide and hold the bottom of said door away from said opening when the upper cam is out of engagement with the track, and a leaf spring mounted on the hanger in contact with said track to yieldingly hold the top portion of the door away from the opening and means for locking said rod against rotation when the upper cam is in engagement with the track. 105

5. The combination with a car having a door opening and a sliding door therefor, of hanging mechanism at the top of the door comprising a track, and a hanger engaging said track, a device operable to force said door laterally into the door opening to close the same, said device comprising a vertical 110 rod rotatably mounted on the door and having a cam projecting from its upper end to engage said track as the rod is rotated and force said door inwardly, a guide at the bottom of said door, a cam on the bottom of said rod adapted to engage the guide and hold the bottom of the door away from said opening when the upper cam is out of engagement with said track. 115

6. The combination with a car having a 120

- door opening and a sliding door therefor, of hanging mechanism at the top of said door comprising a track, and a hanger engaging said track, a device operable to force said door laterally into the door opening, said device comprising a vertical rod rotatably mounted on the door and having a cam projecting from its upper end to engage said track as the rod is rotated and force said door inwardly, a guide at the bottom of said door, a cam on the bottom of said rod adapted to engage the guide and hold the bottom of the door away from said opening when the upper cam is out of engagement with said track, and a leaf spring mounted on said hanger in contact with said track to yieldingly hold the top portion of said door away from said opening.
7. The combination with a car having a door opening and a sliding door therefor, of hanging mechanism at the top of the door comprising a track, and a hanger engaging the track, a device operable to force the door laterally into the door opening, said device comprising a vertical rod rotatably mounted on the door and having a cam projecting from its upper end to engage said track as the rod is rotated and force said door inwardly, a guide at the bottom of the door, a cam on the bottom of the rod adapted to engage said guide and hold the bottom of said door away from the opening when the upper cam is out of engagement with said Z bar, and means for locking said rod against rotation when said upper cam is in engagement with said track.
8. The combination with a sliding door, of hanging mechanism at the top thereof comprising a track, a hanger engaging said track and a device operable to force said door laterally into the door opening, said device comprising a rod rotatably mounted on the door, and having a cam projecting therefrom to engage said track as the rod is rotated, and a leaf spring mounted on said hanger in contact with said track and adapted to force said door laterally out of said opening when said rod is rotated to disengage said cam from said track.
9. The combination with a wall, of a door set into the side thereof, a Z bar track, a hanger comprising a channel rigidly fastened to the door and rollers mounted on the channel and adapted to roll longitudinally along said track and to slide transversely thereof, means manually operable to move the door and hanger laterally into closed position and resilient means positioned between said channel and Z bar adapted to yieldingly hold said door laterally out of closed position.
10. The combination with a wall, of a door set into the side thereof, a track, a hanger rigidly fastened to said door and adapted to move laterally and longitudinally on said track, means manually operable to move the door and hanger laterally into closed position and resilient means adapted to yieldingly hold said door laterally out of closed position and permit longitudinal movement thereof along said track.
11. The combination with a wall having a door opening, of a sliding door adapted to close said opening, a track, a hanger rigidly fastened to the door and engaging said track, manually operable means adapted to force the door and hanger laterally into said opening to close the same, and resilient means operable to force said door laterally out of said opening upon release of said manually operable means.

In testimony whereof, I have hereunto affixed my signature.

THEODORE R. CHANDLER.
